UNITED STATES PATENT OFFICE.

ALBERT M. WARD, OF ROCHESTER, NEW YORK.

SIGNAL.

1,310,813.

Specification of Letters Patent. Patented July 22, 1919.

Application filed October 21, 1918. Serial No. 259,073.

To all whom it may concern:

Be it known that I, ALBERT M. WARD, a citizen of the United States, and resident of Rochester, in the county of Monroe and 5 State of New York, have invented certain new and useful Improvements in Signals, of which the following is a specification.

The present invention relates to signals and more particularly to the type employing 10 a plurality of electrically operated signaling elements in a single structure, an object of this invention being to provide a construction in which a single make-and-break device controls a plurality of circuits of a 15 plurality of signaling devices.

To this and other ends, the invention consists of certain parts and combinations of parts all of which will be hereinafter described, the novel features being pointed out 20 in the appended claims.

In the drawings:—

Figure 1 is a view of a signal embodying the present invention, part of one of the bells being broken away to disclose another 25 bell beneath the same;

Fig. 2 is a side view of the structure shown in Fig. 1;

Fig. 3 is a detail sectional view of the make-and-break device which controls two 30 circuits;

Fig. 4 is a diagrammatic view of the circuits employed in connection with the signal illustrated in Figs. 1 and 2; and

Fig. 5 is a diagrammatic view of the circuits of another embodiment of the invention.

Referring more particularly to the drawings, 1 indicates a base member from which rises a standard 2 on which two signaling 40 devices or bells 3 and 4 are arranged in superposed relation, the uppermost bell being of greater diameter than the under bell. Also arranged upon the base member 1 are two coils 5 and 6 preferably having their 45 axes parallel, and a common pole piece 7 at one end, their other ends each being provided with separated pole pieces indicated at 8 and 9.

Preferably arranged on opposite sides of 50 the coils, with their planes parallel with the

axes of the coils, are two armatures 10 and 11, said armatures being pivoted at 12 and 13, respectively, to the common pole 7, while their swinging or free ends coöperate with the separated pole pieces 8 and 9, respectively. Extended from said armatures are 55 strikers 14 and 15 for coöperating, respectively, with the bells 3 and 4, and forming two signaling devices. A coil spring 16 has its opposite ends secured to extensions 17 on the armatures 10 and 11, and serves to hold the swinging ends of the armatures away from the pole pieces 8 and 9. Movement of the armature under the action of the spring may be varied by adjustable 60 screws 20.

The control of the armatures of the two signaling devices is effected through a single make-and-break device which, in this instance, is in the form of a spring arm 18 secured at 19 to the base plate, and extending laterally therefrom with one of its faces engaged by two arms 20 which project laterally from the armatures 10 and 11 at one side of and toward the center of the pole 75 piece 7. An adjustable screw 21 mounted in an insulator 22 of the pole piece 7 coöperates with this spring contact 18. It is apparent that when either one of the armatures 10 and 11 is drawn toward the respective 80 pole pieces 8 or 9, the laterally projecting arm 20 of said armature will depress the spring contact 18 away from the adjustable contact 21, and thus break the circuit through the make-and-break device. 85

The circuits for controlling the two armatures 10 and 11 may embody two windings 23 and 24 on the coils 5 and 6 connected by a conductor 25 to the make-and-break device 18—21, which, by a conductor 26, leads 90 to the battery 27. The coils 23 and 24, are, respectively, connected to the opposite side of the battery by conductors 28 and 29, which lead, respectively, to the binding posts 30 and 31, and from the latter through the push buttons 32 and 33, respectively, to the battery 27. When the push button 32 is pressed, the coil 5 will be energized and attracts the armature 10, whereas when the push button 33 is pressed, the coil 6 will 100

be energized and the armature 11 will be operated. The make-and-break device 18-21 being common to the circuits of both of the coils 5 and 6 is operated when either 5 one of the armatures is operated.

The signal may also employ a third signaling device in the form of a buzzer comprising an armature 34 pivoted at 35 so as to coöperate with the separated pole pieces 8 and 9, and a spring 36 may normally hold this armature away from said pole pieces, whereas a make-and-break device 37 may control the armature. The operation of this armature 34 is, in this instance, effected through a circuit leading from a push button 38 which is connected with one side of the battery 27, and with a binding post 39 on the base member 1. From this binding post the conductor 40 leads to a second winding 41 in the coil 5, and a second winding 42 in the coil 6, said windings being connected, and the latter winding being connected by a conductor 43 with the make-and-break device 37. From 10 the make-and-break device 37 the circuit leads through the armature 34 to a conductor 44 which is connected with the binding post 45 to which the conductor 26 leading from the make-and-break device 18 is also connected. 15 Pressure on the push button 38 energizes both of the pole pieces 8 and 9, thus effecting the operation of the armature 34. The frequency of the vibration of the armature 34 is greater than either of the armatures 10 and 11, and as a consequence, notwithstanding the fact that the pole pieces 8 and 9 are energized, the armatures 10 and 11 do not operate. Furthermore, the armature 34, while being drawn to the pole pieces 20 8 and 9 when either one of the armatures 10 and 11 is operated, operates in synchronism with said armatures 10 and 11, and in this way does not give any buzzing sound.

In the embodiment of the invention shown 45 in Fig. 5, the construction of the signal is the same except that the coils 5 and 6 have each only one winding 23^a and 24^a. These two windings lead, respectively, from one side of the battery 27 through push buttons 50 32 and 33, connecting with the binding posts 30 and 31, respectively, which lead, respectively, by conductors 28 and 29 to the winding. A conductor 25 leads from both of the windings 23^a and 24^a and connects 55 with the make-and-break device 18-21, which, through the binding post 45, connects with the opposite side of the battery 27. The circuit for the armature 34 embodies the push button 38 connecting with one side 60 of the battery 27 and leading by a conductor 46 to the make-and-break device 37, thence through the armature 34 to a conductor 47, which connects with the wind-

ing 23^a. From the winding 23^a the circuit leads through the conductor 25 to the make-and-break device 18-21, and from the latter to the opposite side of the battery 27. In this construction, as in the other construction, the armature 34 has a greater frequency of vibration than the armature 10, and as a consequence there is no substantial movement of the armature 10 when the armature 34 is operated, while when the armature 10 is operated, the armature 34 operates in synchronism therewith and the buzzing sound is not heard.

In all of the embodiments of the invention it will be seen that there has been provided a construction in which a single make-and-break device is common to the two circuits 80 of two distinctive signaling devices. The construction is such that a symmetrical arrangement of the two signaling devices is obtained with the make-and-break device symmetrically connected to both of said signaling devices. A circuit is provided which permits the ready operation of the two signaling devices through the common make-and-break device.

What I claim as my invention and desire 90 to secure by Letters Patent is:—

1. In a signal, the combination with two coils, independently movable armatures for the coils, and two independently controllable circuits, one for each armature, of a single 95 make-and-break device common to the two circuits and controlled by both of the armatures.

2. In a signal, two coils arranged with their axes parallel, two armatures arranged 100 on opposite sides of the coils and having portions extending laterally toward each other at one end of the coils, and a make-and-break device operable by either one of said laterally extended portions.

3. In a signal, two coils arranged with their axes parallel, two armatures lying on opposite sides of the coils, a third armature arranged at one end of the coils, two make-and-break devices, one controlled by the third armature and the other controlled by both of the first two named armatures, a circuit including at least one of the coils and the make-and-break device of the third armature, a circuit including one of the 110 coils and the other make-and-break device, and a circuit including said last named make-and-break device and the other coil.

4. In a signal, two coils each having two windings, three armatures for the coils, two make-and-break devices, one controlled by one armature and the other controlled by the other two armatures, a circuit including one of the windings of both of the coils and the make-and-break device which is controlled by the single armature, a circuit in-

cluding the other winding of one of the coils and the make-and-break device which is controlled by both armatures, and a circuit including the other winding of the other 5 coil and a make-and-break device which is controlled by both armatures.

5. In a signal, two coils, two independ-

ently movable armatures, one for each coil, a single make-and-break device controlled by both armatures, and two independently 10 controllable circuits one for each armature each including a different coil and the make-and-break device.

ALBERT M. WARD.
